BRIDGING PLUG FOR WELLS AND THE LIKE

Orie O. Dale, Bakersfield, and John D. Chesnut, San Marino, Calif., assignors to International Cementers, Inc., Long Beach, Calif., a corporation of Delaware.

Application November 28, 1947, Serial No. 788,706

16 Claims. (Cl. 166—13)

1

This invention relates to devices of the type commonly called bridging plugs; that is, plugs adapted to be introduced into and set in a well for the purpose of sealing off upper and lower sections of the well pipe or casing. Such plugs can be used to plug the interior of any passage, tube or pipe at any selected point. But as their major use is in oil wells, the invention will be described with that use in mind; its use in analogous situations will be obvious.

Bridging, or other plugs are used in wells for various purposes. In some instances they are constructed so as to be not only settable in the selected location but also to be removable by some special operation and/or special tool. For simplicity of structure, and especially where the plug is used as a temporary bridge to support a plug of poured cement which is subsequently drilled out the plugs are commonly constructed to be drilled out rather than removed intact. The present invention relates primarily to that simple type of plug — that is, a plug adapted merely to be selectively set in position, usually to form a temporary base for building a bridge or plug of cement, plastic, sand or the like.

The essentials of the simple drillable form of bridging plug are as follows. The body or frame is preferably made of some easily drillable material and is provided with a passage either around it or through it (or both) to allow the plug to be lowered in a casing containing well fluid. Those passages (both are usually used) are closed against relative downward fluid movement by valvular means; usually an upwardly facing flexible sealing cup and an upwardly opening check valve. If the plug is merely to be set against downward movement in the casing, the plug is equipped with some kind of casing engaging elements which, when released to set, are forced into casing engagement by relative downward movement of the plug. Wedge slips which move out by relative upward movement on the plug body are commonly used. And if the plug is also to be set against upward movement in the casing, as is desirable, oppositely acting slips are also used. These latter slips, which set only by relative upward movement of the plug in the casing, do not have to have any special control means; but it is necessary, in order to insert the plug to the setting point, that the slips which lock the plug against downward movement be held from action and released only when the setting point is reached. The problem of setting the plug involves primarily the problem of controlling those slips.

Various means, usually involving special setting tools and/or requiring that the plug be lowered on a pipe or rod, have been proposed to solve that problem. The primary characteristic of the present invention lies in its provision of an exception-

2

ally simple and reliable set-controlling arrangement which is easily operated without the need of any special tools or fixtures, which enables the plug to be lowered and operated on a simple flexible line, and which in general provides a plug that is easily and cheaply manufactured in all required sizes.

And a further feature of the invention has to do with the control of a sealing member (e. g. valve) which may be used to close the plug passage against relative upward movement of fluid through the plug. It is desirable that the set plug be sealed against fluid passage either up or down, and the present invention applies the same simple setting control to such a valve as to the slips.

These controls, in general, involve detent members which lie in the path of setting (or closing) movement of the slips (or valve) and which are simply pulled out of their detaining positions by a pull on the lowering line. The detents are, in effect, mere extensions of the lowering line; they may preferably be, as shown here, integral parts of the lowering line. The act of pulling on the lowering line simple pulls the detents of place and removes them with the line from the well.

Another feature of the invention in its preferred form lies in its provision of a skeleton plug body which facilitates low cost manufacture of plugs of different sizes, using standardized parts. The simplicity of the setting controls, involving no relative movable parts which must fit other parts, makes it possible to utilize a simple skeleton body which can be of any size.

The invention is described in preferred and illustrative form in the following description, with reference to the accompanying drawings in which:

Figs. 1 and 2 are vertical longitudinal sections respectively showing the plug as it is lowered in the well, and set in the well, these sections being taken as on line 1—1 of Fig. 3;

Fig. 3 is a horizontal section on enlarged scale on lines 3—3 of Figs. 1 and 4;

Fig. 4 is an enlargement of a portion of Fig. 1;

Figs. 5 and 6 are vertical sections showing modifications;

Fig. 7 is a schematic view at reduced scale showing a typical arrangement for lowering and controlling the plug on a flexible line.

In the drawings, Fig. 1 illustrates one illustrative form of the plug in the condition in which it is lowered into a pipe or well casing 10; and that figure together with Fig. 7 illustrate a typical arrangement of the lowering line or lines 11, 11a on which the plug is lowered and through which the setting control is effected. In Fig. 7 the plug as a whole is generally designated P.

Fig. 2 illustrates the plug in its set condition 60 in the pipe or casing, after being set by pulling

the lowering and control lines away. Figs. 1 and 2 illustrate a form of plug in which the plug passages are sealed merely against relative downward passage of well fluid, cement or other bridge-forming material, when the plug is set. Figs. 5 and 6 illustrate modified forms in which the flow passages are sealed against relative fluid flow both downwardly and upwardly.

As has been stated, the plug and its setting controls are of such form that the plug may be lowered and controlled solely through the medium of a simple flexible line or wire. Such a flexible line is illustratively shown in Fig. 7 at 11, continued (in the form of Fig. 1) by the extension lines 11a which form in full effect direct extensions or integral portions of the supporting line 11. Were it not for the fact that the plug is preferably mainly composed of light-weight materials which are easily drillable, lines 11a might be directly joined to the flexible lowering line 11. However the plug itself is so light that in practice it must be forced down through well liquid. That is most easily done by including a weight in the lowering line directly above the plug. Thus, in Fig. 7 we show schematically a weight W which may represent any suitable object such as a sinker bar or a dump brazier. Fig. 1 which shows the lower end of the weight in detail, shows it as a sinker bar 111 equipped with an attachment 112 to which the lines 11a are secured; the line 11 being connected to the upper end of the sinker bar (weight) as shown in Fig. 7. The weight, whatever it is, may be regarded as being included in the line 11, 11a. Although sufficient weight might be added directly to the plug (e. g. by the simple expedient of placing some heavy material in the upper sealing cup 42) it is preferred to include the weight in the supporting line so that it may be withdrawn when the plug is set.

It is a feature of the invention that such a simple lowering and control means as a flexible line may be used; but the invention is not at all limited against the plug being suspended from and lowered on a rod or pipe or the like. For instance, the extension lines 11a, instead of being joined to the primary line 11, may be connected to any suitable lowering rod or pipe.

As shown in the drawings, the body of the plug is preferably made up of upper and lower head plates 20 and 21 of diameters somewhat smaller than the interior of the pipe in which the plug is intended to operate, and of a plurality of upright slip or gripper guiding members 22 which extend vertically between the upper and lower disks 20 and 21 and are secured to them by any suitable means, such as the screws or bolts 23 in Fig. 3. These slip guides may be of any suitable number, shown as three in the drawings.

Each slip guide preferably carries a set of two slips, one setting by relative upward movement and the other by relative downward movement. The slips may be of any suitable form. Wedges sliding in inclined guide ways are usually used. But for simplicity of manufacture involving no requirement for nicely fitting parts, slips or gripping members in the form of rollers are here preferred.

In each slip guide the relative positions of the upwardly setting and downwardly setting slips or gripping members may be as desired; but for several reasons, particularly that of strength in the design of the slip guides, it is preferred to arrange the pairs of slips in each guide so that the

slip which sets by relative upward movement on the body (holds the body against down movement in the casing) is located in the upper part of the slip guide; with the relatively downwardly setting slip located in the lower part of the slip guide. As will be seen from inspection of Figs. 1 and 2, this arrangement puts the horizontally thickest and strongest part of the slip guide at its center rather than at its top and bottom adjacent the upper and lower plates 20 and 21. With a given amount of material, the arrangement thus makes the slip guide strongest as a beam to resist inward crushing forces due to the wedging action of the slips or grippers.

As shown in the drawings each slip guide comprises an upper and a lower channel formation having a back wall or web 25 and two side walls or flanges 26; a central strengthening web 27, and end formations, such as ears 28, by which the guide is secured to the top and bottom plates. Each channel formation tapers, upwardly or downwardly from the central web 27, and the channel side walls 26 have slip guiding grooves 29. Grooves 29, and back wall 25, of the upper channel formation extend upwardly and outwardly from the center of the guide member; and grooves 29 and the back wall of the lower channel formation extend downwardly and outwardly from the center.

A slip or gripper of the roller type is mounted in each channel formation. As illustrated, each gripper comprises a small roller 30 loosely mounted on a transverse spindle pin 31 whose ends extend beyond the side faces of the roller and into the guide grooves 29. It is not necessary that the spindles fit the guide grooves at all accurately or snugly. The axial or width dimension of the roller 30 is such that it fits between the two opposite channel walls 26 closely enough that the spindle cannot cock to any appreciable angle in the guide grooves. The primary purposes of the projecting pin in the guide grooves is to prevent the roller from falling out of the groove, and also to make simple provision for the attachment of the springs which urge the rollers toward their gripping positions. The engagement of the pins in the guide grooves may be used for the purpose of forcing the rollers outwardly as they move longitudinally of the guides. On the other hand the rollers may be of such size that their peripheries roll on the inclined back walls 25.

It will be noted that the lower rollers 30 could be allowed simply to fall under gravity into their lower pipe gripping positions. It is preferred however to apply springs to those rollers as well as to the upper rollers, to move them into their gripping positions. Tension springs are preferred for the upper rollers, and so similar springs are used for the lower rollers. Thus, in both cases tension springs 35 are mounted in the several grooves 29 and at one end are attached at 35a to the projecting ends of roller spindles 30, and at their other ends are attached, in any suitable manner as indicated at 35b, to the body structure. These springs tend to pull the upper rollers up and the lower rollers down.

In the form of Figs. 1 and 2 upper plate 20 is provided with a central opening 40 adapted to be closed by a downwardly seating ball valve 41. An upwardly facing flexible sealing cup 42 is mounted on the upper face of plate 20, and a ball cage 43 of any suitable design is mounted upon the cup. Cage 43 is of any suitable design

that prevents valve 41 from becoming an upwardly closing one. For instance, as shown in Fig. 2 it may have openings 44 through its side walls.

The effective diameter of the plug shown in the drawings depends solely on the diameters of upper plates 20 and 21 and of sealing cup 42. Thus, a plug of any chosen effective diameter may be made up by using standardized guide and roller assemblies, and mounting them on upper and lower plates of the chosen diameter, and using a sealing cup of the correct diameter. As the sealing cups of various diameters are articles of standard manufacture, plugs of any chosen effective diameter may be made up simply by assembling standardized guide and roller assemblies with the chosen sealing cup and with upper and lower plates of suitable sizes.

Whatever the diametral size of the plug may be, it will be seen from the drawings that the plug body is generally of a skeleton form and that a free open space exists in the central part of the body inside the several guide members. The suspension and control wires 11a are easily strung through this open space and their lower ends are easily put into their locations directly above the spindles of upper rollers 30. As shown in Figs. 1, 3 and 4 the suspension and control wires 11a are strung down through valve cage 43, around ball 41 and through plate opening 40. From there they extend on down and pass through perforations 50, the locations of which are best seen in Figs. 3 and 4. Each perforation 50 intersects one guide groove 29 just above the roller spindle 31 (of the upper rollers 30) when those rollers are in their lowermost positions. The wire 11a, crossing the groove 29 above the roller spindle, is effective in holding the roller down against the upward pull of its springs. Although two such hold-down wires could be used for each upper roller at both ends of its spindle, one is found to be sufficient. The final end of each wire 11a is passed through the portion of perforation 50 which lies outwardly of groove 29 and the terminal wire end is finally bent down as shown at 11c either against the outer surface of the guide member or into a superficial recess which is indicated at 11d.

The purpose of the terminal bend in the wires is to releasably hold the wires in place in such a manner as to require a fairly definite upward pull on the wires in order to pull them out of the plug structure. Any other suitable means or arrangement could be used. For instance, it will be noted that each wire 11a passes through several bends in its extent from the top of the plug to its lower end. As an illustration, there may normally be a rather sharp bend at the point indicated as 11e in Fig. 4; and the bend at that point, together with the frictional contact of the wire in perforation 50, and the frictional contact with the upwardly pressed roller spindle 31, might be utilized as the releasable means for holding the wire in place until a definite upward pull is exerted. Or, the terminal bend at 11c might be made such as to more or less positively lock the end of the wire in place, and the wire could have a weakened portion adjacent that bend; and then the weakened portion would become the definitely releasable means of holding the wire in place. It has been found in practice however that the simple holding arrangement shown in the drawings, and constituting mainly the terminal bend in the wire, is reliably sufficient for the purposes. It

is only necessary that the releasable holding of the wires be strong enough to reliably support the weight of the plug during the lowering operations. The plug is very light (being preferably composed of metal such as magnesium or aluminum in order to be easily drillable) and consequently the relative margin between the weight thrust which the wires normally have to support, and the upward pull which can be easily exerted on the wires, is very large. Such a simple holding means as has been illustrated therefore suffices.

As shown in Figs. 1 and 7, where a line-included weight is used to force the plug down, the sinker bar 111 may have a fitting 112 threadedly attached to its lower end. The fitting 112 has a lower end recess 113 that fits over valve cage 43 with the lower edge of the fitting resting directly on the plug. Wires 11a extend upwardly from the valve cage through holes 114 in the fitting and then have their upper ends secured in any suitable manner, as by simply tying them around the shank of 112. The plug is thus held up closely against the weight fitting with no looseness between the plug and the weight. Similar means can be used for attaching the plug to a dump, or to a length of cable-suspended pipe, or to the lower end of a string of tubing, etc.

The operation of the device of Figs. 1 and 2 follows from the foregoing description. In preparation for lowering in the well the suspension and control wires 11a are put in place to hold the upper gripper rollers 30 in their lowermost positions. On stopping the downward movement at the selected setting point, or on the inception of an upward pull on the suspension line, the lower grippers 30 set automatically to hold the plug against further upward movement. Continued upward pull on the suspension line 11 then pulls the suspension and control wires 11a away from their positions over the spindles of the upper gripper rollers. The upper gripper rollers then immediately move up to their gripping positions of Fig. 2 where they prevent downward movement of the plug. Removal of the suspension and control wires also pulls them past ball valve 41, allowing it to fall on to its seat. The plug is thus set in the casing against either downward or upward movement, and the passages through and around the plug are closed to prevent downward movement of any fluid past or through it.

Fig. 5 shows one variational form of the plug, equipped with valvular means for sealing the plug against both downward and upward movements of fluid. The device as there shown is the same as that shown in Figs. 1 to 4, with certain additions. The same numerals are applied to duplicate parts of Fig. 4 and those duplicate parts will need no repeated description.

In Fig. 5, the lower body plate 215 is made in the form of a flat plate without the guide lugs 21a that are shown in Figs. 1 and 2. A downwardly facing flexible sealing cup 425 is mounted on the lower face of plate 215, and an upwardly seating ball valve 415 is adapted to close the central opening 21b with which both plate 21 (Figs. 1 and 2) and plate 215 are provided. A valve cage 435 encloses ball 415, and the ball valve is normally urged up by valve spring 41a. When this valve closes onto its seat around opening 21b it prevents relative upward movement of fluid through the plug. In order to hold the ball off its seat during lowering of the plug through well fluid, a wire or wires which in effect

form extensions of the other suspension and control wires may be inserted between the ball and its seat. Thus, for instance, two additional suspension and control wires 115 (in addition to the three wires 11a) may be added to the group of suspension and control wires. These two additional wires 115 extend downwardly past upper ball 41 like the others and then extend on down and have their terminal ends, at 115a inserted between lower ball 415 and its seat. These terminal ends may be bent somewhat as illustrated under the lower face of plate 215 so that those bends also function as releasable holding or detent means for the suspension and control wires. The extra wires 115 are pulled out of place and pulled away from the plug in the same manner as before described, allowing ball 415 to seat at the same time that the upper expanding gripper rollers 30 are allowed to move to position to lock the plug against downward movement. In Fig. 5 all the wires 11a and 115 are shown simply as extending above the plug, to be connected in any of the manners before described.

Fig. 6 shows another variant form which in major respects is a duplicate of the design shown in Figs. 1 and 2. Duplicate numerals are applied to duplicate parts, and only the changed or additional features will be described.

In this form of Fig. 6 the lower plate 21 is the same as plate 21 of Fig. 1. The downwardly facing flexible sealing cup 426 is attached to the upper head plate 206 under the upwardly facing cup 42 and the valve cage 436. The upwardly seating valve 416 is located in the upper valve cage 436, along with the downwardly seating ball valve 41. That downwardly seating ball 41 is the same in action as ball 41 of Figs. 1 and 2, except that it is urged downwardly not only by gravity but also by the spring 41b which lies between the two balls and also urges ball 416 upwardly toward its seat which surrounds the opening 43b at the upper end of cage 36. In Fig. 6 cage 436 is an imperforate cage so that fluid can only pass through it vertically by passing through the upper opening 43b and the lower opening 40 in the upper body plate 20. The suspension and control wires 11a are the same wires as shown in Figs. 1 and 2. They perform the function of releasably holding the upper rollers 30 down, as before explained; and they not only pass around the lower ball 41, but also around the upper ball 416 to hold that ball down off its seat during lowering of the plug through well fluid.

The operation of this form is the same as before described. The plug can be lowered through well fluid while ball 416 is held off its seat; and when the plug is set by the operations before described the removal of the wires releases both valve balls 41 and 416 to seat and to seal the passage through the plug against both upward and downward relative movements of fluid.

In the foregoing description and in the following claims the directional terms "down," "up" and "vertical," and similar terms, are used respectively and collectively in the senses of the direction in which the plug is inserted in the pipe or other opening or passage, and the opposite direction.

Regardless of the nature of the specific means by which the plug is lowered and set in the well, whether that means involves a string of pipe, or a simple flexible wire or cable weighted or unweighted, to which the support and control

wires 11a, 115, are connected or directly attached or of which they form a part; that means as a whole may be regarded as a supporting and control "line" of which the wires 11a, 115, form a part or a continuation. The term "line" is used in that sense in the following claims, without any limitation to a flexible line such as a wire or cable unless specifically so stated.

We claim:

1. In settable pipe plugs of the type which include a plug body, gripping means mounted on the body and adapted to engage a pipe wall to lock the body against relative upward movement in the pipe, a second gripping means mounted on the body and adapted to engage the pipe wall to lock the body against relative downward movement in the pipe, said second gripping means being movable with relation to the body between a position out of pipe engagement and a position in pipe engagement, and means urging the second gripping means from the non-engaging to the engaging position; plug placing and setting means comprising a detent receiving passage in the plug body extending across the path of movement of the second gripping means, a supporting and control line, a detent which forms a continuation of said line and is adapted to lie in said receiving passage across said path of movement of the gripping means to hold that gripping means in non-engaging position, and means forming a part of the detent and line and normally holding the detent in said passage, said last named means being releasable by an upward pull exerted on the supporting and control line.

2. Plug placing and setting means as defined in claim 1 and in which the supporting and control line comprises, at least in part, a flexible wire, and the detent forms a part of the same flexible wire.

3. Plug placing and setting means as defined in claim 1 and in which the detent and the supporting and control line at least in part are portions of a length of flexible wire, and in which the detent holding means is formed as a bent portion of said wire.

4. In settable pipe plugs of the type which include a plug body, gripping means mounted on the body adapted to engage a pipe wall to lock the body against relative upward movement in the pipe, an upwardly and outwardly extending guide in the body, a pipe-wall gripper movable along said guide from a lower position out of engagement with the pipe to an upper pipe engaging position, and means urging the gripper upwardly along the guide; plug placing and setting means comprising a detent receiving passage in the plug body extending across the path of movement of the gripper, a supporting and control line, a detent which form a continuation of said line and is adapted to lie in the receiving passage across the path of movement of the gripper to hold the gripper in its lower position, and means forming a part of the detent and line and normally holding the detent in the passage, said last named means being releasable by an upward pull exerted on the supporting and control line.

5. Plug placing and setting means as defined in claim 4 and in which the detent and the supporting and control line at least in part are portions of a length of flexible wire.

6. Plug placing and setting means as defined in claim 4 in which the detent and the support-

ing and control line at least in part are portions of a length of flexible wire, and in which the detent holding means is formed as a bent portion of said wire.

7. In settable pipe plugs of the type stated in claim 1 and which also include a vertical valve-seated passage through the plug body and an upwardly closing valve controlling that passage; plug placing and setting means as defined in said claim 1 and also comprising a detent connected with the supporting and control line and adapted to lie removably in a position between the valve and the valve seat.

8. Plug placing and setting means as defined in claim 7, and in which the valve detent, and the supporting and control line at least in part, are portions of a length of flexible wire.

9. In settable pipe plugs of the type stated in claim 4 and which also include a vertical valve-seated passage through the plug body and an upwardly closing valve controlling that passage; plug placing and setting means comprising a detent receiving passage in the plug body extending across the path of movement of the gripper, a supporting and control line which at least in part is in the form of a flexible wire a portion of which is adapted to lie in the detent receiving passage across the path of movement of the gripper to hold the gripper in its lower position, and a bend in the flexible wire engaging the body and adapted to releasably hold the end portion of the wire in the passage.

10. A settable pipe plug of the type described, comprising a plug body having upper and lower heads, a plurality of vertically extending guide members extending between and secured to the heads, and each of the guide members having an upwardly and outwardly extending guide and a downwardly and outwardly extending guide; pipe grippers movable in said guides, springs urging the upwardly-and-outwardly-movable grippers upwardly along their guides, a detent receiving passage in each guide member extending across the path of movement of the upwardly movable grippers, a supporting and control line, a plurality of detents formed as extensions of the line and adapted to be positioned in the detent receiving passages to hold the upwardly-and-outwardly-movable grippers in lower positions in their guides, and means associated with the detents to normally hold them in the passages, said means releasable by an upward pull exerted on the supporting and control line.

11. A settable pipe plug as defined in claim 10 and in which the several guide members are spaced from each other in open formation about an open central space, in which the upper head has a central opening through it, and in which the detents are formed as parts of flexible wires extending down through the opening and extending their ends into the detent receiving passages.

12. A settable pipe plug as defined in claim 10 and in which the several guide members are spaced from each other in open formation about an open central space, in which the upper head has a central opening through it, and in which the detents are formed as parts of flexible wires extending down through the opening and extending their ends into the detent receiving passages, and in which the detent holding means are formed as bends in the flexible wires engaging portions of the guide members.

13. A settable pipe plug as defined in claim 10, and in which the detent receiving passages extend through the guide members from one face to an opposite face, in which the detents are formed as parts of flexible wires which are parts of the supporting line, the detent wires extending through the detent receiving passages and protruding their ends beyond one guide member face, and in which the detent holding means are bends in the protruding ends of the detent wires.

14. A settable pipe plug as defined in claim 10 and in which the several guide members are spaced from each other in open formation about an open central space, in which both upper and lower heads have central openings which, with the open central space, form a vertical passage through the plug body, a valve seat and an upwardly closing valve associated with the vertical passage, and in which the supporting line has flexible wire extensions which form the detents and also extend to positions between the valve and valve seat.

15. A settable pipe plug of the type described, comprising a plug body having upper and lower head plates with central openings through them, a plurality of vertically extending guide members extending between and secured to the head plates, said guide members spaced in open formation about an open central space which, with the head plate openings, forms a vertical passage through the plug body, a valve seat and an upwardly closing valve associated with one of the head plate openings, each guide member having its upper part formed as an upwardly and outwardly extending guide and its lower part formed as a downwardly and outwardly extending guide, upper and lower pipe grippers movable in the several guides, springs urging the upper grippers upwardly, detent receiving passages in each upper guide extending through the guide across the path of movement of the gripper therein and extending from a guide face which is adjacent the central body space to an opposite outer guide face, a supporting and control line, flexible wires forming parts of the line, the line extending through the upper head plate opening and the ends of some of the wires extending through the detent receiving passages with their ends protruding beyond an outer guide face, the protruding ends of the wires being bent to form holding means releasable by a pull exerted on the supporting line, and some of the wires extending between the valve and valve seat.

16. A settable pipe plug as defined in claim 15 and in which the pipe grippers are formed as rollers with central pins which engage the guides.
